UNITED STATES PATENT OFFICE.

FORÉE BAIN, OF LA GRANGE, ILLINOIS.

SPARK-PLUG.

1,319,318.

Specification of Letters Patent. Patented Oct. 21, 1919.

Application filed October 11, 1918. Serial No. 257,681.

To all whom it may concern:

Be it known that I, FORÉE BAIN, a citizen of the United States, residing at La Grange, in the county of Cook and State of Illinois, have invented certain new and useful Improvements in Spark-Plugs, of which the following is a specification.

My invention relates to improvements in spark plugs.

10 The object of my invention is to produce a spark plug that will eliminate all of the trouble heretofore incident to devices of this character, due to excessive heat, and which will contribute to the efficient operation of 15 the engine, by supplying fresh air for rendering the initial ignition more certain and more effective; which will prevent premature explosions due to abnormal heating of the electrodes by compression of the engine 20 charge; which will maintain the spark gap clean and free of carbon deposit and contribute to the longevity of the plug by preventing absorption of carbon by the porcelain insulator and preventing fracture 25 thereof by the extreme high temperature to which it is usually subjected.

I accomplish these objects by automatically cooling and cleaning the terminals or electrodes of the plug, with a draft of incoming air directed against the surfaces of 30 the terminals and by automatically bringing the terminals forcibly together and then separating them, to mechanically remove or displace deposits thereon by their impact, at 35 least once during each operative cycle of the engine.

Still another object of my invention is to provide a plug which will accomplish all of the above desirable results and which 40 also provides a convenient and very efficient means for initially priming the engine to render starting more easily to be accomplished.

Other, further and more specific objects 45 of my invention will become readily apparent to persons skilled in the art, from a consideration of the following description when taken in conjunction with the drawings, wherein:—

50 Figure 1 is a central longitudinal section of the improved spark plug, embodying my invention.

Fig. 2 is a section, taken on line 2—2 of Fig. 1.

In both the views the same reference characters are employed to indicate similar parts.

5 is the shell of a spark plug, threaded at its base end, as at 6, for insertion in the cylinder of an engine, and threaded, as at 7, 60 for the threaded thimble 8. 9 is the porcelain core having a central or axial perforation extending longitudinally thereof, as at 10, and enlarged, preferably to provide a valve receiving cavity, as at 11. A gasket 65 12 is included between the shell 5 and the porcelain core and another gasket 13 is included between the thimble 8 and the core, whereby to properly hold the core in position in the metal parts, as usual in structures of this character.

A cap 15 has its lower edge 16 spun or pressed inwardly over a shoulder 17 of the porcelain core 9 to hold the cap in place, the part 18 being threaded, as at 19, for insertion of the perforate threaded plug 20. A check nut 21 holds the plug in adjusted position with reference to the cap.

The plug 20 is perforated with a relatively large bore, as at 21, to serve as a receptacle 80 for priming liquid fuel, and a relatively small bore, as at 22, to constrict the passage of air. The bore 22 terminates in a valve port 23 normally closed by a valve 24. The valve is located at the upper termination of 85 the central stem conductor 25. The stem 25 is shown to be rectangular in cross section, as in Fig. 2, thereby leaving air spaces between the bore 10 of the core 9 and the rectangular stem 25. The squared portion of 90 the stem terminates, as at 26, above which portion, as at 28, it is round. The valve 24 is normally held on its seat by an open helical spring 29. The stem 25 terminates, as at 95 30, in an electrical terminal or electrode in co-operation with a fixed electrode 31. Wire binding nut 33 is threaded on plug 20.

During the suction stroke of the engine, the valve 24 is opened, thus drawing the stem 25 and the valve 24 downwardly until 100 the electrodes 30 and 31 are in actual contact. This result is produced by the suction of the engine against the resilient tension of the spring 29. Thus a draft of fresh air is

drawn in through the openings 21, 22 and 10, which is forcibly directed against the electrodes 30 and 31, thus keeping the core 9 and the stem 25 cool and cooling the electrodes by the lower temperature of the air taken in, in the manner described. At the same time that the air is drawn in, the electrodes 30 and 31 are brought into contact by the impact of the upper movable electrode 30, with the lower electrode 31, thus tending to loosen or displace any carbon deposit that may be attached to either of the electrodes which the draft of air will carry away into the cylinder.

15 The air taken in at the plug, unlike the carbon dioxid usually surrounding the electrodes thereof, is a supporter of combustion and the incipient explosion caused by the spark in the presence of the air is greatly enhanced, rendering propagation of flame more rapid and increasing the efficiency of the engine.

At the end of the suction stroke and at the beginning of the compression stroke, the 25 valve 24 will be seated and close the port 23, and therefore the openings 21 and 22, and prevent egress of any of the cylinder contents through the plug.

The spring 29 normally closes the valve 30 but its use is not essential. If the spring 29 were not present the valve would be seated at the beginning of the compression stroke and held closed by the air that would be forced into the longitudinal axial opening 10 and in that event the valve would be closed only at the time when the pressure within the cylinder is greater than that of the outside atmosphere.

The receptacle 121 in the screw threaded 40 plug 20, is enlarged sufficiently to contain a charge of gasoline or other fluid fuel, as a means for priming the engine in starting it, as when the weather is cold, or when the carburetor is not working satisfactorily 45 for this purpose.

When the receptacle 121 is filled with gasoline, or the like, it is held therein and not admitted into the cylinder until at the time of the suction stroke, whereby it will 50 be pulverized or atomized by the incoming air instead of lying upon the top of the piston head or run out through the valves as when admitted by the usual priming cock when the piston is at the upper end of its 55 stroke.

When the plug is used in engines having mechanically operated intake valves it is well to delay opening of said intake valves for a short period of time at the beginning 60 of the suction stroke of the piston in order to produce a short air impulse of high velocity through the plug. The spring 29 may be tempered to suit engines having mechanically operated or suction operated

valves. In either case the spring 29 should be just sufficient to hold the valve 24 closed except when there is a vacuum tendency in the engine cylinder as the increase of pressure in the cylinder will maintain the valve closed after being seated by the spring.

70 While I have herein shown a single embodiment of my invention, for the purpose of clear disclosure, it is manifest that many changes may be made in the relation and configuration of the parts within the 75 scope of the appended claims.

Having described my invention, what I claim is:—

1. A spark plug having in combination an insulating, axially perforated core, providing an axial valve-containing cavity in its upper end and a shoulder surrounding the cavity; a centrally perforated, threaded cap, having a skirt tucked in at its lower edge around said shoulder; an axially perforated threaded plug having two bores with a valve seat at its lower end, adjustable in said cap, a check nut to hold the plug in adjusted position and a central conductor terminating at its upper end in a 85 valve to close the port in the lower end of the plug.

2. A spark plug having in combination an axially perforated core with an enlarged chamber in its upper end; a perforated 95 threaded cap fixed to and held by the upper end of the core; a perforated threaded plug adjustable in said cap and having a valve seat in its lower end and a valve in said core chamber adapted to close the perforation in 100 the plug.

3. A spark plug having in combination an axially perforated core with an enlarged chamber in its upper end; a perforated 105 threaded cap fixed to and held by the upper end of the core; a perforated threaded plug adjustable axially in said cap and having a valve seat in its lower end and an enlarged chamber in its upper end; a check nut to hold the plug in adjusted position and a 110 valve in the core chamber adapted to close the perforation in the plug.

4. A spark plug having in combination an axially perforated core with an enlarged chamber in its upper end; a perforated 115 threaded cap fixed to and held by the upper end of the core; a perforated threaded plug adjustable in said cap and having a valve seat in its lower end; a check nut to hold the plug in adjusted position; a valve in 120 said core chamber adapted to close the perforation in said plug; a valve stem extending loosely through the axial perforation of the core and a spring in the core chamber to normally close the valve.

5. A spark plug having in combination an axially perforated core having an enlarged opening at its upper end; a valve in

said opening having a stem extending directly through said perforation; a threaded cap overlying said opening and fixed to the upper end of the core; a threaded plug vertically adjustable in said cap and carrying a valve seat and a spring in said opening to

move the valve for normally closing the opening in the core.

In testimony whereof I hereunto subscribe my name.

FOREE BAIN.
